MACHINE FOR APPLYING ADDRESS LABELS
TO MAILING PIECESJames E. Doane, Chicago, Ill., assignor to
Cheshire Mailing Machines, Inc., Chicago, Ill.,
a corporation of Illinois

Application September 6, 1949, Serial No. 114,255

27 Claims. (Cl. 216—30)

1

This invention relates to improvements in machines for applying an address strip to a mailing piece and relates particularly to improvements in mailing machines for applying address strips to envelopes, small pamphlets or the like.

In the mailing of mass circulated letters or small pamphlets it has been the practice to employ coiled strips having customers' or subscribers' names and addresses intervally spaced thereon, each name and address being separated by a perforation, the so perforated strips being acted upon by a mailing head which intervally feeds the strip, applies paste to the reverse side thereof, severs the strip and affixes the severed strip to the magazine or paper.

Heretofore in such addressing or mailing machines it has been the practice to move the mailing pieces individually by means of a conveyor chain having lugs engaging the mailing pieces. In such machines the mailing pieces were momentarily halted by disengagement of the lugs with the mailing piece, and during the momentary halt the severed and pasted label was applied to the mailing piece. A second chain conveyor having lugs thereon then engaged the addressed mailing piece for removal from the machine.

In the machines of the prior art, mechanical means have been employed to advance a proper length of mailing strip, apply paste thereto, and then sever and apply the pasted strip to the mailing piece, the operation being timed in accordance with the spacing and speed of feed of the mailing pieces. Since the mailing head incorporating such mechanical means was operated from the feeding mechanism for the mailing pieces, the flexibility thereof was necessarily limited, and it was not possible readily to adjust the position of the mailing head according to different sizes of mailing pieces or according to different places of application of the pasted and severed address label.

With the foregoing considerations in mind it is a principal object of the invention to enable mail pieces to be handled in a mailing machine without the necessity of employing lug bearing chain conveyors for transporting the individual mail pieces, a belt conveyor being employed for transporting the mail pieces, an intermittently operating arresting device being employed for holding the mail piece in position for the application thereto of an addressed label by a mailing head, the belt meanwhile continuing to move beneath the mail piece and thereafter removing the mail piece upon release of the arresting mechanism from the mailing head for action by the mailing head on following mailing pieces.

2

Another important object is to enable the perforated mailing strip to be fed and measured by the action of electrical mechanism controlled by the perforations of the mailing strip and the movement of a mailing piece moving along the belt conveyor.

Still another object comprehends the provision of a circuit for controlling the operation of a mailing head for a mailing machine, and to operate electrical mechanism associated with the mailing head to feed, sever and apply a perforated label to a mailing piece which affects the operation of the control circuit.

An auxiliary object to those mentioned above is to feed mailing pieces without the necessity of using lugs for engaging each mail piece, thereby eliminating the possibility of damaging the edges of the mailing pieces.

A further object comprehends the provision of a mailing head which can be oriented to one of several positions according to the size of the mailing piece and the desired position of a pasted and severed label to be applied to the mailing piece.

Yet another object is the provision of a mailing head which will operate with perforated address strips of various sizes, the mailing head being characterized by electrical means sensing the spacing of the perforations and advancing an individual address label in accordance with the distance between the perforations.

The foregoing and other objects of the invention will be apparent from a study of the following description taken together with the drawings which illustrate a preferred embodiment of the invention and what is now considered to be the best mode of applying the principles thereof. While the invention is described in terms of an embodiment which it may assume in practice, it is not intended to be limited in terms of the embodiment shown, nor otherwise than by the terms of the appended claims.

In the drawings:

Figure 1 is a plan view of an improved mailing machine according to the present invention;

Figure 2 is a front elevation view thereof;

Figure 3 is an enlarged front elevation view of the feed table portion of the mailing machine shown in Figures 1 and 2;

Figure 4 is a view taken along the line 4—4 of Figure 3, certain parts being shown in section and certain other parts being shown in side elevation;

Figure 5 is an enlarged plan view of the mailing head of the mailing machine shown in Figures 1 and 2;

Figure 6 is a section taken along the line 6—6

of Figure 5 looking in the direction of the arrows;

Figure 7 is a rear elevation view of the mailing head shown in Figure 5;

Figure 8 is an enlarged transverse section through the mailing head of Figure 5 along the line 8—8 of Figure 5 and looking in the direction of the arrows;

Figure 9 is an enlarged plan view of the paste trough of the mailing head of Figure 5 taken along the line 9—9 of Figure 8 and looking in the direction of the arrows;

Figure 10 is a partly plan and partly schematic view of a power shaft showing certain electrical control apparatus for the mailing head of Figure 5 mounted thereon;

Figure 11 is a view looking in the direction of the arrows 11—11 of Figure 10 and showing certain electrical control apparatus associated therewith;

Figure 12 is a view looking in the direction of the arrow 12—12 of Figure 10 and showing a portion of a circuit controlling the mailing head of Figure 5;

Figure 13 is a view looking in the direction of the arrows 13—13 of Figure 10 and showing the arresting mechanism for a mailing piece;

Figure 14 is a circuit diagram for the electrical control apparatus shown in Figures 10 to 13;

Figure 15 is a schematic showing the circuit and control for the arresting mechanism of Figure 13;

Figure 16 is a schematic showing the circuit and control for the severing mechanism shown in Figures 5 to 9 inclusive; and

Figure 17 is a detailed partly plan and partly sectional view of the valve operator for the suction valve shown in Figures 2 to 4 inclusive.

Referring now to Figures 1 and 2 of the drawings the improved mailing machine according to the present invention includes a flat table or bed 20 resting upon a generally rectangular frame 21 which in turn is supported upon vertical members 22 and horizontal stiffener members 23. The support structure is mounted upon casters 24 for easy portability of the machine. Generally, the mailing machine may be considered as including a feeding mechanism indicated generally at 26, a mailing head portion indicated generally at 27 and a delivery portion indicated generally at 28.

Referring now particularly to Figures 2, 3 and 4 of the drawings, the feeding portion 26 of the mailing machine includes a motor 29, mounted upon the horizontal stiffener members 23, for supplying power through a pair of pulleys 31 and 32 to drive a power shaft 33. As seen in Figure 4, the power shaft 33 is journaled in depending brackets 34 secured to the underside of the rectangular frame 21. The power shaft 33 is provided with an eccentric 35 which cooperates with an eccentric connecting rod 37 pivotally connected at 38 to a lug 39 formed on the bottom side of a shuttle table 41. As seen in Figure 4, the shuttle table is adapted to slide in slots 42 formed on platelike members 43 secured in any convenient manner to the bed 20.

The bed 20 has affixed thereto a bracket 44 which spans the shuttle table 41, and which provides a support for a pair of adjustable guides 46 having flanges 47 struck out therefrom which may be adjusted and held in position by means of bolts 48 passing through slots 49 formed in the bracket 44. The table 20 also supports a pair of arms 51 which support a table 53 for storing

mailing pieces to be fed to the machine according to the present invention. As seen in Figure 3, the table 53 is formed with a boss 54 which forms a guide for a rod 56 secured in any convenient fashion to an adjustable guide 57, the arrangement being such that the guide 57 may be adjusted in position according to the size of the mailing pieces 58 to be addressed by the machine.

10 The bracket 44 includes a pair of arms 59 which support an adjusting screw 61 which adjusts the position of a gate 62 upward or downward depending upon the thickness of each individual mailing piece 58, see also Figure 4. It will be seen that the guide 57, the gate 62 and the adjustable side guides 46 define a hopper for mailing pieces 58 to be fed to the mailing machine.

15 The shuttle table 41 is provided with a plurality of lugs 63 which are of a height less than the thickness of each mailing piece. The lugs 63 are adapted to engage the back edge of an individual mailing piece and to carry the mailing piece 58 forward upon the forward reciprocating movement of the shuttle table 41. Each individual mailing piece is thus advanced between a pair of feed rollers 64 and 66, feed rollers 66 being fast

20 on a shaft 67 which is driven by a pinion 68, also fast to the shaft 67, which is driven from a gear

25 69 fast to the power shaft 33. The feed rollers 64 are adapted to idle upon a shaft 71 which is journaled in an end bracket arm 72 and which is pivoted at 73 to the brackets 44. The pressure

30 of the idler feed rollers 64 on the feed rollers 66 in feeding a mailing piece 58 may be varied

35 by an adjusting screw 74 threaded into the arm 72. The adjusting screw bears against a spring 75 which is bottomed against the bed 20 and is held in position by a boss 76 protruding upward therefrom.

40 Each individual mailing piece which has been engaged by the feed rollers 64 and 66 is moved thereby on to a conveyor 76 consisting of a plurality of belts which are trained around a driving pulley 77 fast on a shaft 78, see particularly Figures 2 and 4.

45 An idler gear 79 mounted upon an idler shaft 81 is adapted to mesh with the pinion 68 and to mesh with a drive pinion 82 fast on the shaft 78 to drive the pulley 77.

50 As seen in Figure 2, the conveyor belt 76 is trained around an idler pulley 83 mounted on a shaft 84 at the delivery end of the bed 20. A tension idler pulley 80 is mounted on an adjusting device 85 supported by the horizontal stiffener members 23 to adjust the tension of the

55 conveyor belts 76.

56 Since the machine according to the present invention is particularly adapted to place addressed labels on envelopes or small pamphlets

60 which are lighter than the usual mass-circulated magazine, means are provided for applying suction to the underside of the bottommost mailing piece 58 held within the hopper, so that it may be positively separated from the mailing

65 pieces lying thereabove. To this end there is provided a motor 86, see Figure 2, which drives a suction pump 87. The suction pump 87 is

70 connected by a conduit 88 to a vacuum reservoir 89 which in turn is connected by a flexible

75 vacuum line 91 to a valve block 92. The valve block 92 is secured to the shuttle table 41 in any convenient fashion and is adapted to move therewith.

76 The valve block 92 has a port 93 therein which communicates with a chamber 94, the chamber 94 communicating with openings 95

of a foraminous plate 97 having a depression 95, and adapted to rest upon the valve block 92 and within an opening formed in the shuttle plate 41. A shuttle valve 98 is adapted to slide in a bore 99 formed in the valve body 92 and is provided with a reduced annular portion 101 which at times is in register with the port 93 so that suction will be applied to the openings 96 in the foraminous plate 97.

Referring now to Figure 17, the shuttle valve 98 has a slotted connection 102 with a bell crank 103 pivotally mounted at 104 to a support 106 adapted to reciprocate with the shuttle table 41. The bell crank 103 has an arm 107 adapted to lie between two adjustable stops 108 and 109 which are fastened to the underside of the bed 20, see also Figure 4. The shuttle valve 98 is so designed that its reduced annular portion 101 is in register with the port 93 at the start of the reciprocating movement of the shuttle table 41 toward the feed rollers 64 and 65 and is closed at the end of such forward reciprocating movement when the feed rollers 64 and 66 have engaged the individual mailing piece and are moving the mailing piece to the right, as seen in Figure 4, to be transported on the conveyor belt 76. It will be apparent from Figure 17 that the shuttle valve 98 is closed at the forward end of the stroke, and that when the valve block 92 has moved back to the start position the bell crank 103 will be rocked in a counterclockwise position, as seen in Figure 17, to once more open the valve 98.

Means are provided for holding the individual mailing pieces against the conveyor belt 76 and to this end, see particularly Figures 1, 2 and 3, a pair of hold-down straps 111 are provided which may be adjusted to move up or down according to the thickness of each mailing piece together with the gate 62. As shown in Figure 3, the gate 62 is provided with a boss 112 which threadably supports an arm 113 connected to a lifting member 114 secured to the straps 111.

The mailing pieces may be additionally held down during their transport by the conveyor belt 76, by guides 116 which extend for substantially the length of the bed 20 and may be additionally guided by side guide members 117 which may be adjusted in or out along guide rods 118 according to the dimension of the mailing pieces, see Figure 1.

Referring now particularly to Figures 5 to 9 inclusive, each individual mailing piece is adapted to move past the mailing head 27 and to be momentarily arrested in its motion along the conveyor belt 76, by means later to be described, for the application thereto of a pasted and severed label having a mailing address thereon. The mailing head 27 includes a square base structure 119 having vertical ribs 121 and horizontally extending flanges 122, the ribs 121 being adapted to fit within a pair of rails 123 which overlie the bed 20 and which are supported at each end on brackets 120 resting on the bed 20. The square base structure 119 is thus adapted to rest on the rails 123 to support the mailing head 27 above the bed 20. It will be seen that the mailing head 27 can be oriented through 90° to any one of three positions.

The base structure 119 supports a pair of bracket arms 124 which support a roll of address strip 126, each address being separated by a perforation, as may be shown in Ralph E. Doane application Serial No. 757,188, now abandoned, filed June 26, 1947, Machine and Process for Making Mailing Strips. The perforated mailing strip 126 is lead past a guide roller 127 and be-

tween a slightly knurled or serrated feed roller 128 and a pressure roller 129, see Figure 9. The feed roller 128 is adapted to turn within a reservoir 131 for liquid paste or other suitable adhesive, supported in any convenient manner on the base structure 119. The feed rollers 128 are fast on a shaft 132 journaled in the side walls of the reservoir 131, and are driven by a plurality of miter gears 133, 134, 135 and 136 which are drivably connected to a motor 137 supported by the base structure 119.

10 The amount of paste or liquid adhesive to be carried by the feed rollers 128 is regulated by a plurality of scraper fingers 138 at the end of a scraper arm 139 which may be adjusted in position by means of the knurled adjusting nut 141, see also Figure 6.

15 The pressure roller 129 is journaled at each end in a pair of arms 142, see Figure 5, which are 20 connected together by an arm 143. The arm 143 is connected by a member 135b which is pin connected as at 135a to an armature 147 of a solenoid 148, see Figure 6. The position of the arms 142 may be adjusted by adjusting screws 149 25 tapped into the end of the bracket arm 142 remote from the pressure roller 129.

20 The perforated tape 126 is lead across a guide plate 151 and between the feed rollers 128 and the pressure roller 129. Since the feed rollers 128 30 are turning constantly, the perforated tape will be advanced only when the pressure roller 129 is brought against the feed rollers 128 with the perforated strip 126 therebetween, the pressure rollers 129 being moved in such direction upon energization of the solenoid 148 upon a condition as 35 will appear later in this description.

30 The feed rollers 128 and the pressure roller 129 are adapted to advance the perforated strip 126 past a knife edge 153 where the strip is severed 40 by a combined label shearing and applying arm 154. The arm 154 is provided with a lug 156 which is connected by a pin 157 to a clevis 158 formed at the end of an arm 159. The arm is fast on a shaft 162 and is provided with an extension 163 and an adjustable stop 164. In rocking to the 45 label applying position the adjustable stop 164 impinges against a pin 140 supported slidably by a standard 150 and urged to the right as seen in Figure 7 by a spring 145. The shaft 162 has an arm 166 extending therefrom which is connected 50 by a link 167 to the armature 168 of a solenoid 169. It will be apparent that when the solenoid 169 is energized, the attraction of the armature 168 will rock the shaft 162 together with the arm 159 in a counterclockwise direction, as in Figure 55 7, to sever a label from the perforated strip which has been fed by the feed rollers 128 and the pressure roller 129, and that upon further counterclockwise movement of the arm 159 the pasted and severed label will be applied to a mailing 60 piece which is in position beneath the mailing head 27. The spring 145 opposes the movement of the arm 159 in moving to the label applying position under the action of the solenoid 169 and tends to lessen the impact of the arm 154 upon a mailing piece.

65 The mailing head 27 is formed with a frame and guard 171 which includes an arm 171a which extends over the label applying arm 154. The arm 171a is provided with a boss 155 which supports a pin 160 which is drilled at 165 to guide a rod 170 formed integrally with the lug 156. It will be apparent that as the arm 159 is moved in a counterclockwise direction, as seen in Figure 7, the guide rod 170 will cause the arm 154 to lie 75 flat against a mailing piece 58 thereunderneath.

The shaft 162 is encircled by a spring 175, see Figure 5, which opposes the counterclockwise movement of the arm 159 upon energization of the solenoid 169 and provides for release of the arm and rotation thereof in a clockwise direction upon deenergization of the solenoid 169.

The mailing head is provided with means for sensing a perforation in the address strip 126 and thereupon to close a circuit including the winding of the solenoid 169 upon conditions to be described later in this specification. As seen particularly in Figures 5, 6 and 8, bracket arms 142 are spanned by a tie rod 172 journaled in supports 172a on the support frame 119. The tie rod 172 supports a mounting 173 for a thin metallic strip 174 having a plurality of sensing fingers 176 thereon. The flexible fingers are adapted to drop into a perforation in the strip 126 and to make contact with the contact plate 152. At times when the flexible fingers 176 are contacting points between said perforations, the circuit including the contact plate 152 will be broken.

Mechanism is provided for controlling the operation of the mailing head 27 so that the arm 159 is rocked by the solenoid 169 to apply a severed and pasted label to a mailing piece. As shown with particular reference to Figures 4, 10 and 14, the power shaft 33 is provided with a cam 178 which controls a switch 179.

Referring now to Figures 2 and 14, the bed 20 is provided with a normally closed switch 181 having a sensing finger 182 which is adapted to open the switch 181 when depressed by a mailing piece 58 being transported by the conveyor belt 76. The switches 179 and 181 are connected in parallel with respect to each other through branching leads 183 and 184 which are connected by a lead 186 through a relay 187, the circuit being completed by a lead 188 through a step-down secondary of a transformer 189 and thence by a lead 191 through the sensing fingers 176, the contact plate 152 and a lead 192. The switch 181 and the contact points 176 and contact plate 152 are normally operable to keep the relay 187 energized. However, when a mailing piece 58 is being transported over the finger 182 by the conveyor belt 76, it depresses the finger and opens the switch 181, thereby deenergizing the relay 187 allowing the closing of a circuit which includes a conduit 193, the solenoid 148, a lead 194 and closed contact points 196 of the relay 187, and thence to the other side of the supply line. With the relay 148 thus energized, the pressure roller 129 will be brought into contact with the feed roller 128, since the arms 142 will rock about the tie rod 172. Since the feed rollers 128 are constantly rotating, the perforated strip 126 will be advanced until a circuit is made by the sensing fingers 176 closing on the contact plate 152, and provided also if the switch 181 is closed because of the mailing piece having been transported beyond the finger 182. However, if the mailing piece 58 is of such a dimension so that the switch 181 will have remained in open condition, a parallel circuit will be closed which includes the sensing finger 176 and the contact plate 152 and the cam operated switch 179. With the contact made between the sensing finger 176 and the contact plate 152 and contact made on either switch 181 or switch 179, the relay 187 will be energized once more, thereby opening the contacts 196 and deenergizing the solenoid 148 to cause disengagement of the pressure roller 129 with the feed roller 128.

The power shaft 33 is also adapted to control the energization of the solenoid 169. As shown

with particular reference to Figures 4, 10 and 12, the power shaft 33 is provided with a cam 197 which closes a switch 198 which energizes the solenoid 169 to operate the label applying arm 154 through the arm 159, the circuit being completed through the solenoid 169 by conduits 199 and 201 to a source of power.

Arresting means are provided for arresting the progress of the mailing pieces 58 on the conveyor belt 76 and to stop the mailing piece beneath the label applying arm 154 for the application thereto of a pasted and severed label. As shown with particular reference to Figures 4, 10, 13 and 15, the power shaft 33 is provided with a cam 202 which is so timed as to operate a switch 203 which energizes a solenoid 204 having a moving armature 206 which engages the forward edge of a mailing piece 58 and holds same in arrested position for the application thereto of a pasted and severed label.

The mailing piece which has been acted upon by the mailing head 27 is then removed by the conveyor belt 76 to the delivery end 28, and on to a delivery belt 207, see particularly Figures 1 and 2. The delivery belt 207 is trained around a drive pulley 208 driven by a gear 209 which meshes with a gear 211 driven by a motor 212. The delivery belt 207 is also trained around an idler pulley 213. An arm 214 is pivoted at a hub 216 to one of the guide rods 118, and supports a roller 217 for slowing down the mailing pieces 58, and so that they may be stacked against a stop 218.

It will be apparent from the foregoing description that the sequence of events which have been described will be repeated for each mailing piece as it moves over the conveyor belt 76. The power shaft 33 together with its actuating cams and the sensing switch 181 determines the sequence of operation of the pressure and feed rollers 129 and 128 and the operation of the label severing and applying arm 154, and also the operation of the arresting means for each mailing piece as it is being acted upon by the mailing head 27. According to the present invention, it is possible to apply address labels to mailing pieces without the need of conveying the mailing pieces with lug bearing chains which engage and then release the mailing pieces for application thereto of a severed and pasted strip. According to the present invention it is possible to perform the mailing operation of mailing pieces of different dimensions and to perform the mailing operation on pieces irrespective of their weight. As herein described, the mailing head 27 may be moved to any one of three positions so that the address labels may be applied to the mailing pieces in any desired position. By the use of the electrical control circuits according to the present invention the machine is extremely flexible and adapted to be employed with different sizes of mailing pieces.

While the invention has been described in terms of an embodiment which it may assume in practice, it is not intended that the scope of the invention be limited in terms of the embodiment shown nor otherwise than by the claims here appended.

I claim:

1. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed

roller to advance an intervally perforated strip having mailing addresses thereon, a label shearing and applying arm adapted to sever and apply a label which has been advanced by said pressure roller and by said feed roller, and circuits for controlling said mailing head comprising a first circuit including a switch operable by said mailing pieces as they are moved along said conveying means, a second switch connected in series with said first switch and operable in accordance with the spacing of the perforations on said strip, electrical means responsive to the operation of said switches to move said pressure roller into engagement with said feed roller with said intervally perforated strip held therebetween to advance said intervally perforated strip a distance as determined by the spacing of said perforations, means including a cam and switch operated by said conveying means for arresting a mailing piece being conveyed by said conveying means to hold said mailing piece in position for application of a label thereto by said label shearing and applying arm, and means including a cam and switch operated by said conveying means for actuating said label shearing and applying arm to apply a severed label to a mailing piece which has been arrested in position by said arresting means.

2. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second switch connected in series with said first switch and operable in accordance with the spacing of the perforations on said strip, a relay adapted to be actuated upon operation of either of said switches, electrical means operable upon actuation of said relay to move said pressure roller into engagement with said feed roller with said intervally perforated strip held therebetween to advance said intervally perforated strip a distance as determined by the spacing of said perforations, means including a cam and switch operated by said conveying means for arresting a mailing piece being conveyed by said conveying means to hold said mailing piece in position for application of a label thereto by said label shearing and applying arm, and means including a cam and switch operated by said conveying means for actuating said label shearing and applying arm to apply a severed label to a mailing piece which has been arrested in position by said arresting means.

3. In a mailing machine of the type wherein mailing pieces are moved by conveying means at regularly spaced intervals for application thereto of an address label: a mailing head for severing an address label from a strip and applying same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits

for controlling said mailing head comprising a first circuit including a switch operable by said mailing pieces as they are moved along said conveying means, a second circuit including a cam actuated switch operated by said conveying means and connected in parallel with said first named circuit, said cam-actuated switch being adapted to be closed before the closing of said first named switch, a third switch connected in series with said first switch and said cam-actuated switch and operable in accordance with the spacing of the perforations of said strip, electrical means responsive to the operation of any one of said series connected switches to move said pressure roller into engagement with said feed roller with said intervally perforated strip held therebetween to advance said intervally perforated strip a distance as determined by the spacing of said perforations, means including a cam and switch operated by said conveying means for arresting a mailing piece being conveyed by said conveying means to hold said mailing piece in position for application of a severed label thereto by said label shearing and applying arm, and means including a cam and switch operated by said conveying means for actuating said label shearing and applying arm to apply a severed label to a mailing piece which has been arrested in position by said arresting means.

4. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second circuit including a cam-actuated switch operated by said conveying means and connected in parallel with said first named circuit, said cam-actuated switch being adapted to be closed before the closing of said first named switch, a third switch connected in series with said first switch and said cam-actuated switch and operable in accordance with the spacing of the perforations of said strip, a relay adapted to be actuated upon operation of either of said switches, electrical means operable upon actuation of said relay to move said pressure roller into engagement with said feed roller with said intervally perforated strip held therebetween to advance said intervally perforated strip a distance as determined by the spacing of said perforations, means including a cam and switch operated by said conveying means for arresting a mailing piece being conveyed by said conveying means to hold said mailing piece in position for application of a severed label thereto by said label shearing and applying arm, and means including a cam and switch operated by said conveying means for actuating said label shearing and applying arm to apply a severed label to a mailing piece which has been arrested in position by said arresting means.

5. In a mailing machine of the type wherein mailing pieces are moved by conveying means at regularly spaced intervals for application thereto of an address label: a mailing head for severing

11

an address label from a strip and applying the same to a mailing piece comprising a paste applying feed roller, a pressure roller cooperating with said paste applying feed roller to advance an intervally perforated strip having mailing addresses thereon, a label shearing and applying arm adapted to sever and apply a pasted label which has been advanced by said pressure roller and said paste applying feed roller, and circuits for controlling said mailing head comprising a first circuit including a switch operable by said mailing pieces as they are moved along said conveying means, a second switch connected in series with said first switch and operable in accordance with the spacing of the perforations on said strip, electrical means responsive to the operation of said switches to move said pressure roller into engagement with said paste applying feed roller with said intervally perforated strip held therebetween to advance said intervally perforated strip a distance as determined by the spacing of said perforations, means including a cam and switch operated by said conveying means for arresting a mailing piece being conveyed by said conveying means to hold said mailing piece in position for application of a pasted and severed label thereto by said label shearing and applying arm, and means including a cam and switch operated by said conveying means for actuating said label shearing and applying arm to apply a pasted and severed label to a mailing piece which has been arrested in position by said arresting means.

6. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second switch connected in series with said first switch and operable in accordance with the spacing of the perforations on said strip, electrical means responsive to the operation of either of said switches to move said pressure roller into engagement with said feed roller with said intervally perforated strip held therebetween to advance said intervally perforated strip a distance as determined by the spacing of said perforations, a solenoid having a moving armature for arresting a mailing piece being conveyed by said conveying means to hold said mailing piece in position for application of a pasted and severed label thereto by said label shearing and applying arm, a second cam-actuated switch operated by said conveying means for controlling said solenoid, and means including a cam and switch operated by said conveying means for actuating said label shearing and applying arm to apply a pasted and severed label to a mailing piece which has been arrested in position by said solenoid.

7. In a mailing machine of the type wherein mailing pieces are moved by conveying means at regularly spaced intervals for application thereto of an address label: a mailing head for severing an address label from a strip and applying the

12

same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second switch connected in series with said first switch and operable in accordance with the spacing of the perforations on said strip, electrical means responsive to the operation of either of said switches to move said pressure roller into engagement with said feed roller with said intervally perforated strip held therebetween to advance said intervally perforated strip a distance as determined by the spacing of said perforations, a solenoid having a moving armature for arresting a mailing piece being conveyed by said conveying means to hold said mailing piece in position for application of a severed label thereto by said label shearing and applying arm, a second cam-actuated switch operated by said conveying means for controlling said solenoid, a solenoid actuator for said label shearing and applying arm, and a third cam-actuated switch operated by said conveying means for controlling the operation of said solenoid actuator.

8. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to apply a label which has been advanced by said pressure roller and said feed roller, and circuits for controlling said mailing head comprising a first circuit including a switch operable by said mailing pieces as they are moved along said conveying means, a second switch connected in series with said first switch and operable in accordance with the spacing of the perforations on said strip, a relay adapted to be actuated upon operation of either of said switches, electrical means operable upon actuation of said relay to move said pressure roller into engagement with said feed roller with said intervally perforated strip held therebetween to advance said intervally perforated strip a distance as determined by the spacing of said perforations, a solenoid having a moving armature for arresting a mailing piece being conveyed by said conveying means to hold said mailing piece in position for application of a severed label thereto by said label shearing and applying arm, a second cam-actuated switch operated by said conveying means for controlling said solenoid, and means including a cam and switch operated by said conveying means for actuating said label shearing and applying arm to apply a severed label to a mailing piece which has been arrested in position by said solenoid.

9. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having

mailing addresses thereon, a label shearing and applying arm adapted to apply a label which has been advanced by said pressure roller and said feed roller, and circuits for controlling said mailing head comprising a first circuit including a switch operable by said mailing pieces as they are moved along said conveying means, a second switch connected in series with said first switch and operable in accordance with the spacing of the perforations on said strip, a relay adapted to be actuated upon operation of either of said switches, electrical means operable upon actuation of said relay to move said pressure roller into engagement with said feed roller with said intervally perforated strip held therebetween to advance said intervally perforated strip a distance as determined by the spacing of said perforations, a solenoid having a moving armature for arresting a mailing piece being conveyed by said conveying means to hold said mailing piece in position for application of a severed label thereto by said label shearing and applying arm, a second cam-actuated switch operated by said conveying means for controlling said solenoid, a solenoid actuator for said label shearing and applying arm, and a third cam-actuated switch operated by said conveying means for controlling the operation of said solenoid actuator.

10. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to apply a label which has been advanced by said pressure roller and said feed roller, and circuits for controlling said mailing head comprising a first circuit including a switch operable by said mailing pieces as they are moved along said conveying means, a second circuit including a cam-actuated switch operated by said conveying means and connected in parallel with said first named circuit, said cam-actuated switch being adapted to be closed before the closing of said first named switch, a third switch connected in series with said first switch and said cam-actuated switch and operable in accordance with the spacing of the perforations of said strip, a relay adapted to be actuated upon operation of said switches, electrical means operable upon actuation of said relay to move said pressure roller into engagement with said feed roller with said intervally perforated strip held therebetween to advance said intervally perforated strip a distance as determined by the spacing of said perforations, a solenoid having a moving armature for arresting a mailing piece being conveyed by said conveying means to hold said mailing piece in position for application of a severed label thereto by said label shearing and applying arm, a second cam-actuated switch operated by said conveying means for controlling said solenoid, a solenoid actuator for said label shearing and applying arm, and a third cam-actuated switch operated by said conveying means for controlling the operation of said solenoid actuator.

11. A mailing head for a mailing machine of the type in which mailing pieces are conveyed at regularly spaced intervals along a bed extending longitudinally of said mailing machine for the application by said mailing head of a

pasted and severed label having a mailing address thereon to a mailing piece: a base frame having a square outline adapted to rest upon spaced rails overlying said bed and to be oriented in any one of three 90° apart positions with respect to said bed, a reservoir for a quantity of liquid adhesive, a feed roller mounted for rotation in said reservoir and to carry a film of said adhesive along the periphery thereof, a guide for a perforated strip having mailing addresses between the perforations thereon, a pressure roller adapted to move into contact with the feed roller with the perforated strip therebetween to coat said strip with adhesive and advance same, a shear knife over which said perforated strip is advanced, an intermittently operated solenoid for moving said pressure roller in a direction towards said feed roller to advance said strip, a label severing and applying arm for severing the strip which has been advanced by said feed roller and said pressure roller, and means for actuating said label severing and applying arm after said perforated strip has been so advanced.

12. A mailing head for a mailing machine of the type in which mailing pieces are conveyed at regularly spaced intervals along a bed extending longitudinally of said mailing machine for the application by said mailing head of a pasted and severed label having a mailing address thereon to a mailing piece: a base frame having a square outline adapted to rest upon spaced rails overlying said bed and to be oriented in any one of three 90° apart positions with respect to said bed, a reservoir for a quantity of liquid adhesive, a feed roller mounted for rotation in said reservoir and to carry a film of said adhesive along the periphery thereof, a guide for a perforated strip having mailing addresses between the perforations thereon, a pressure roller adapted to move into contact with the feed roller with the perforated strip therebetween to coat said strip with adhesive and advance same, a shear knife over which said perforated strip is advanced, an intermittently operated solenoid for moving said pressure roller in a direction towards said feed roller to advance said strip, a label severing and applying arm for severing the strip which has been advanced by said feed roller and said pressure roller, and a solenoid for actuating said label severing and applying arm after said perforated strip has been so advanced.

13. A mailing head for a mailing machine of the type in which mailing pieces are conveyed at regularly spaced intervals along a bed extending longitudinally of said mailing machine for the application by said mailing head of a pasted and severed label having a mailing address thereon to a mailing piece: a base frame having a square outline adapted to rest upon spaced railings overlying said bed and to be oriented in any one of three 90° apart positions with respect to said bed, a reservoir for a quantity of liquid adhesive, a feed roller mounted for rotation in said reservoir and to carry a film of said adhesive along the periphery thereof, a guide for a perforated strip having mailing addresses between the perforations thereon, a pressure roller adapted to move into contact with the feed roller with the perforated strip therebetween to coat said strip with adhesive and advance same, a shear knife over which said perforated strip is advanced, an intermittently operated solenoid for moving said pressure roller in a direction towards said feed roller to advance said strip, a switch including a contact plate over which said perforated strip is

adapted to pass and including a movable switch finger adapted to close on said contact plate when in register with one of said perforations for controlling the operation of said intermittently operating solenoid, a label severing and applying arm for severing the strip which has been advanced by said feed roller and said pressure roller, and means for actuating said label severing and applying arm after said perforated strip has been so advanced.

14. A mailing head for a mailing machine of the type in which mailing pieces are conveyed at regularly spaced intervals along a bed extending longitudinally of said mailing machine for the application by said mailing head of a pasted and severed label having a mailing address thereon to a mailing piece: a base frame having a square outline adapted to rest upon spaced rails overlying said bed and to be oriented in any one of three 90° apart positions with respect to said bed, a reservoir for a quantity of liquid adhesive, a feed roller mounted for rotation in said reservoir and to carry a film of said adhesive along the periphery thereof, a guide for a perforated strip having mailing addresses between the perforations thereon, a pressure roller adapted to move into contact with the feed roller with the perforated strip therebetween to coat said strip with adhesive and advance same, a shear knife over which said perforated strip is advanced, an intermittently operated solenoid for moving said pressure roller in a direction towards said feed roller to advance said strip, a switch including a contact plate over which said perforated strip is adapted to pass and including a movable switch finger adapted to close on said contact plate when in register with one of said perforations for controlling the operation of said intermittently operating solenoid, a label severing and applying arm for severing the strip which has been advanced by said feed roller and said pressure roller, and a solenoid for actuating said label severing and applying arm after said perforated strip has been so advanced.

15. A mailing head for a mailing machine of the type in which mailing pieces are conveyed at regularly spaced intervals along a bed extending longitudinally of said mailing machine for the application by said mailing head of a pasted and severed label having a mailing address thereon to a mailing piece: a base frame, a reservoir for a quantity of liquid adhesive, a feed roller mounted for rotation in said reservoir and to carry a film of said adhesive along the periphery thereof, a guide for a perforated strip having mailing addresses between the perforations thereon, a pressure roller adapted to move into contact with the feed roller with the perforated strip therebetween to coat said strip with adhesive and advance same, a shear knife over which said perforated strip is advanced, an intermittently operated solenoid for moving said pressure roller in a direction towards said feed roller to advance said strip, a label severing and applying arm for severing the strip which has been advanced by said feed roller and said pressure roller, and means for actuating said label severing and applying arm after said perforated strip has been so advanced.

16. In a mailing machine for applying an addressed label to a mailing piece wherein mailing pieces are fed to a pair of feed rollers for movement thereby to a bed having a conveyor thereon for transport of individual mailing pieces at regularly spaced intervals: a power shaft for driving

said feed rollers to move an individual mailing piece into position for transport by said conveyor; a mailing head for severing an address label from a strip and applying the same to a mailing piece comprising a feed roller, a pressure roller cooperating with said feed roller to advance an intervally perforated strip having mailing addresses between said perforations, a label shearing and applying arm adapted to apply an address label

10 which has been advanced by said pressure roller and said feed roller, and circuits for controlling said mailing head comprising a first circuit including a switch operable by said mailing pieces as they are moved along said conveyor, a second switch connected in series with said first switch

15 and operable in accordance with the spacing of the perforations on said strip, electrical means responsive to the operation of either of said switches to move said pressure roller into engagement with said feed roller with said intervally perforated strip held therebetween to advance said intervally perforated strip a distance as determined by the spacing of said perforations, means including a cam mounted on said power shaft and a switch actuated by said cam for arresting the movement of a mailing piece being conveyed by said conveyor to hold said mailing piece in position for application of a label thereto by said label shearing and applying arm, and

20 means including a second cam mounted on said power shaft and a switch actuated by said second cam for actuating said label shearing and applying arm to apply a severed label to a mailing piece which has been arrested in position by said arresting means.

25 17. In a mailing machine for applying an addressed label to a mailing piece wherein mailing pieces are fed to a pair of feed rollers for movement thereby to a bed having a conveyor thereon for transport of individual mailing pieces at regularly spaced intervals: a power shaft for driving

30 said feed rollers to move an individual mailing piece into position for transport by said conveyor, a mailing head for severing an address label from a strip and applying the same to a mailing

35 piece comprising a feed roller, a pressure roller cooperating with said feed roller to advance an intervally perforated strip having mailing addresses between said perforations, a label shearing and applying arm adapted to apply an address label which has been advanced by said pressure roller and said feed roller, and circuits for controlling said mailing head comprising a first circuit including a switch operable by said mailing pieces as they are moved along said conveyor,

40 a second switch connected in series with said first switch and operable in accordance with the spacing of the perforations on said switch, a relay adapted to be actuated upon operation of

45 either of said switches, electrical means operable upon actuation of said relay to move said pressure roller into engagement with said feed roller with said intervally perforated strip held therebetween to advance said intervally perforated

50 strip a distance as determined by the spacing of said perforations, means including a cam mounted on said power shaft and a switch actuated by said cam for arresting the movement of a mailing piece being conveyed by said conveyor to hold

55 said mailing piece in position for application of a label thereto by said label shearing and applying arm, and means including a second cam mounted on said power shaft and a switch actuated by said cam for actuating said label shearing and applying arm to apply a label to a mailing piece

60 65 70 75

which has been arrested in position by said arresting means.

18. In a mailing machine for applying an addressed label to a mailing piece wherein mailing pieces are fed to a pair of feed rollers for movement thereby to a bed having a conveyor thereon for transport of individual mailing pieces at regularly spaced intervals: a power shaft for driving said feed rollers to move an individual mailing piece into position for transport by said conveyor, a mailing head for severing an address label from a strip thereof and applying the same to a mailing piece comprising a feed roller, a pressure roller cooperating with said feed roller to advance an intervally perforated strip having mailing addresses between said perforations, a label shearing and applying arm adapted to apply an address label which has been advanced by said pressure roller and said feed roller, and circuits for controlling said mailing head comprising a first circuit including a switch operable by said mailing pieces as they are moved along said conveyor, a second circuit including a second switch and a cam mounted on said power shaft for operating said switch, said second circuit being connected in parallel with said first named circuit, said cam operated switch being adapted to be closed before the closing of said first named switch, a third switch connected in series with said first switch and said cam operated switch and operable in accordance with the spacing of the perforations of said strip, electrical means responsive to the operation of any one of the series connected switches to move said pressure roller into engagement with said feed roller with said intervally perforated strip held therebetween to advance said intervally perforated strip a distance as determined by the spacing of said perforations, means including a cam mounted on said power shaft and a switch actuated by said cam for arresting the movement of a mailing piece being conveyed by said conveyor to hold said mailing piece in position for application of a label thereto by said label shearing and applying arm, and means including a second cam mounted on said power shaft and a switch actuated by said second cam for actuating said label shearing and applying arm to apply a severed label to a mailing piece which has been arrested in position by said arresting means.

19. In a mailing machine for applying an addressed label to a mailing piece wherein mailing pieces are fed to a pair of feed rollers for movement thereby to a bed having a conveyor thereon for transport of an individual mailing piece at regularly spaced intervals, a power shaft for driving said feed rollers to move individual mailing pieces into position for transport by said conveyor, a mailing head for severing an address label from a strip and applying the same to a mailing piece comprising a feed roller, a pressure roller cooperating with said feed roller to advance an intervally perforated strip having mailing addresses between said perforations, a label shearing and applying arm adapted to apply a severed address label which has been advanced by said pressure roller and said feed roller, and circuits for controlling said mailing head comprising a first circuit including a switch operable by said mailing pieces as they are moved along said conveyor, a second switch connected in series with said first switch and operable in accordance with the spacing of the perforations on said strip, electrical means responsive to the operation of either of said switches to move said

pressure roller into engagement with said feed roller with said intervally perforated strip held therebetween to advance said intervally perforated strip a distance as determined by the spacing of said perforations, a solenoid having a moving armature for arresting a mailing piece being conveyed by said conveyor to hold said mailing piece in position for application of a severed label thereto by said label shearing and applying arm, a second cam actuated switch operated by said power shaft for controlling said solenoid, and means including a second cam mounted on said power shaft and a switch actuated by said cam for actuating said label shearing and applying arm to apply a severed label to a mailing piece which has been arrested in position by said arresting means.

20. In a mailing machine for applying an addressed label to a mailing piece wherein mailing pieces are fed to a pair of feed rollers for movement thereby to a bed having a conveyor thereon for transport of an individual mailing piece at regularly spaced intervals, a power shaft for driving said feed rollers to move individual mailing pieces into position for transport by said conveyor, a mailing head for severing an address label from a strip and applying the same to a mailing piece comprising a feed roller, a pressure roller cooperating with said feed roller to advance an intervally perforated strip having mailing addresses between said perforations, a label shearing and applying arm adapted to apply a severed address label which has been advanced by said pressure roller and said feed roller, and circuits for controlling said mailing head comprising a first circuit including a switch operable in accordance with the spacing of said mailing pieces along said conveyor, a second switch connected in series with said first switch and operable in accordance with the spacing of the perforations on said switch, electrical means responsive to the operation of either of said switches to move said pressure roller into engagement with said feed roller with said intervally perforated strip held therebetween to advance said intervally perforated strip a distance as determined by the spacing of said perforations, a solenoid having a moving armature for arresting a mailing piece being conveyed by said conveyor to hold said mailing piece in position for application of a severed label thereto by said label shearing and applying arm, a second cam actuated switch operated by said power shaft for controlling said solenoid, a solenoid actuator for said label shearing and applying arm, and a third cam actuated switch operated by said power shaft for controlling the operation of said solenoid actuator.

21. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and by said feed roller, and circuits for controlling said mailing head comprising a first circuit including a switch operable by said mailing pieces as they are moved along said conveying means, a second switch connected in series with said first switch and operable in accordance with the spacing of the perforations on

said strip, electrical means responsive to the operation of said switches to move said pressure roller into engagement with said feed roller with said intervally perforated strip held therebetween to advance said intervally perforated strip a distance as determined by the spacing of said perforations, means for arresting a mailing piece being conveyed by said conveying means to hold said mailing piece in position for application of a label thereto by said label shearing and applying arm, and means for actuating said label shearing and applying arm to apply a severed label to a mailing piece which has been arrested in position by said arresting means.

22. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second switch connected in series with said first switch and operable in accordance with the spacing of the perforations on said strip, a relay adapted to be actuated upon operation of either of said switches, electrical means operable upon actuation of said relay to move said pressure roller into engagement with said feed roller with said intervally perforated strip held therebetween to advance said intervally perforated strip a distance as determined by the spacing of said perforations, means for arresting a mailing piece being conveyed by said conveying means to hold said mailing piece in position for application of a label thereto by said label shearing and applying arm, and means for actuating said label shearing and applying arm to apply a severed label to a mailing piece which has been arrested in position by said arresting means.

23. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second circuit including a cam actuated switch operated by said conveying means and connected in parallel with said first named circuit, said cam-actuated switch being adapted to be closed before the closing of said first named switch, a third switch connected in series with said first switch and said cam actuated switch and operable in accordance with the spacing of the perforations of said strip, electrical means responsive to the operation of any one of said series connected switches to move said pressure roller into engagement with said feed roller with said intervally perforated strip

held therebetween to advance said intervally perforated strip a distance as determined by the spacing of said perforations, means for arresting a mailing piece being conveyed by said conveying means to hold said mailing piece in position for application of a severed label thereto by said label shearing and applying arm, and means operated by said conveying means for actuating said label shearing and applying arm to apply a severed label to a mailing piece which has been so arrested.

24. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second circuit including a cam-actuated switch operated by said conveying means and connected in parallel with said first named circuit, said cam-actuated switch being adapted to be closed before the closing of said first named switch, a third switch connected in series with said first switch and said cam-actuated switch and operable in accordance with the spacing of the perforations of said strip, a relay adapted to be actuated upon operation of either of said switches, electrical means operable upon actuation of said relay to move said pressure roller into engagement with said feed roller with said intervally perforated strip held therebetween to advance said intervally perforated strip a distance as determined by the spacing of said perforations, means for arresting a mailing piece being conveyed by said conveying means to hold said mailing piece in position for application of a severed label thereto by said label shearing and applying arm, and means operated by said conveying means for actuating said label shearing and applying arm to apply a severed label to a mailing piece which has been so arrested.

25. In a mailing machine of the type wherein mailing pieces are moved by conveying means at regularly spaced intervals for application thereto of an address label: a mailing head for severing an address label from a strip and applying the same to a mailing piece comprising a feed roller, a pressure roller cooperating with said feed roller to advance an intervally perforated strip having mailing addresses thereon, a label shearing and applying arm adapted to sever and apply a label which has been advanced by said pressure roller and said feed roller, and circuits for controlling said mailing head comprising a first circuit including a switch operable by said mailing pieces as they are moved along said conveying means, a second switch connected in series with said first switch and operable in accordance with the spacing of the perforations of said strip, electrical means responsive to the operation of either of said switches to move said pressure roller into engagement with said feed roller with said intervally perforated strip held therebetween to advance said intervally perforated strip a distance as determined by the spacing of the perforations of said strip,

21

ing of said perforations, a solenoid having a moving armature for arresting a mailing piece being conveyed by said conveying means to hold said mailing piece in position for application of a pasted and severed label thereto by said label shearing and applying arm, means for controlling said solenoid, and means operated by said conveying means for actuating said label shearing and applying arm to apply a pasted and severed label to a mailing piece which has been arrested in position by said solenoid.

26. A mailing head for a mailing machine of the type in which mailing pieces are conveyed at regularly spaced intervals along a bed extending longitudinally of said mailing machine for the application by said mailing head of a pasted and severed label to a mailing piece: comprising a reservoir for a quantity of liquid adhesive, a feed roller mounted for rotation in said reservoir and to carry a film of adhesive along the periphery thereof, a pressure roller adapted to move into contact with said feed roller with the perforated strip therebetween to coat said strip and advance same, means for intermittently moving said pressure roller in a direction toward said feed roller to advance said strip, a label severing and applying arm for severing the strip which has been advanced by said feed and pressure

22

rollers, and means for actuating said label severing and applying arm after said strip has been so advanced.

27. A mailing head for a mailing machine of the type in which mailing pieces are conveyed at regularly spaced intervals along a bed extending longitudinally of said mailing machine for the application by said mailing head of a pasted and severed label to a mailing piece: comprising a reservoir for a quantity of liquid adhesive, a feed roller mounted for rotation in said reservoir and to carry a film of adhesive along the periphery thereof, a pressure roller adapted to move into contact with said feed roller with the perforated strip therebetween to coat said strip and advance same, means for intermittently moving said pressure roller in a direction toward said feed roller to advance said strip, switch means cooperating with said feed roller for controlling said last named means, a label severing and applying arm for severing the strip which has been advanced by said feed and pressure rollers, and means for actuating said label severing and applying arm after said strip has been so advanced.
